OPHTHALMIC MOUNTING

Robert Malcom, Chicago, Ill.

Application August 31, 1938, Serial No. 227,836

8 Claims. (Cl. 2—14)

This invention relates to the bridge members that connect the eyecups or other lens holders of goggles or other ophthalmic mountings, and more particularly to means to adjust the length of those members to conform the cups comfortably and in eye alinement to the facial characteristics of a user.

The bridge member is elongated and flexible, and it has a series of enlargements. It may be a conventional ball-chain as shown, or it may be of other suitable form having a series of enlarged parts affording abutments to cooperate with parts hereinafter described.

It is an object of the invention to provide means, for connecting a bridge member of this kind to one or both of the lens holders, so arranged that the member easily may be varied in length between the holders so that the latter may be spaced to meet the requirements of a user.

Another object is to provide means that will retain the bridge member in association with a lens holder without liability of disconnection therefrom or change in the adjustment.

Further, the invention provides a connecting means so formed that a flexible bridge of the kind referred to may be shortened simply by pulling it past the holding part of the connection.

Other characteristics of the invention are apparent in the following description.

The invention is exemplified herein in association with goggles, and for convenience and brevity the lens holders are referred to as eyecups, but it is to be understood that the disclosure made and terms used are intended to denote also equivalent parts of any ophthalmic mounting to which the invention is applicable, and that it is not limited to mountings of the goggle type.

Like reference-characters refer to corresponding parts in the views of the drawing, of which—

Fig. 1 is a front view of a pair of goggles;

Fig. 2 is an enlarged section through one of the eyecups on line 2—2, Fig. 1;

Fig. 3 is a section on line 3—3, Fig. 2;

Fig. 4 is a view of the spring arm;

Fig. 5 is a view of another form of that arm;

Fig. 6 is a section similar to Fig. 3 illustrative of use of another form of bridge member;

Fig. 7 is a fragmentary section, as on line 2—2, Fig. 1, the arm being omitted.

Goggles, of the type shown for purpose of exemplification, include conventional eyecups 11 with rigid circular side walls 12 shaped at their inner edges to conform to average facial con-

tours, and having at the outer edges lenses 13 held in place by retaining rings 14 screwed onto the cups, the cups also having members 15 for connection with a headband (not shown), as is common in the art.

The eyecups are connected by a bridge 16. The bridge comprises an elongated flexible member having a series of abutments for cooperation with locking means in the eyecups. As shown in Figs. 1, 2, and 3, the flexible bridge member may be formed of a plurality of balls 17 connected in spaced relation by a series of link members 18; or, as shown in Fig. 6, it may be a chain 19, links of which constitute abutments. The bridge member may be covered between the cups by a tube 20 of rubber or other soft material as a cushion at the bridge of the nose.

In order to permit the flexible bridge member to traverse through side walls of the eyecups in adjusting the length of the bridge, each of those walls is perforated in the nasal side to provide a hole or passage 21 large enough to permit movement therethrough of the abutment parts of the bridge member. The wall at the inner end of the hole is reamed out and enlarged at one side 22 to a somewhat oval shape, as indicated at 22, in a place that is under the slot of a locking arm now described.

Adjusting movement of the bridge member is permitted and that member locked by a somewhat thin spring arm 23 of sheet metal or other suitable material, one of which is positioned inside of each eyecup. The arm is formed with an enlarged end portion 24, a shank 25 extending therefrom, and an enlarged approximately circular terminal portion 26. The portion 26 is concave or cupped as shown at 27, and a flange 28 surrounds the cup. A slot 29 extends from the periphery through the flange into the cup whereby fingers 30 are afforded. The slot may extend from the periphery at the end of the arm as shown in Fig. 4 or it may extend from a side as shown in Fig. 5.

The arm is permanently fixed at its enlarged end 24 to the wall of the eyecup by rivets 31 or other suitable fasteners as shown in Figs. 2 and 3, or it may have at that end an integral pin 31a that seats in a depression in the eyecup as shown in Fig. 6, whereby a single rivet or the like together with the pin prevents lateral swing of the arm. The attachment is such that the cup 27 seats in the end of the hole 21 and the flange 28 against the wall of the eyecup, the flange being large enough to overlap that wall. The slot 29 is of a size to permit link members 18 or links 55

of the chain 19, as the case may be, to be received between the fingers 30. The cup is of a size to permit ball members 17 to seat therein.

With an abutment of the flexible bridge member (whether a ball of the ball-chain form, a link of the chain form, or the equivalent abutting part of some other suitable form) seated in the cup 27 and with the fingers 30 straddling the member, the bridge member is locked and lengthening thereof under pull while the goggles are in use is prevented; and, when the bridge member is slack while the goggles are not in use, its movement in shortening direction is prevented by the arm. As the flange 28 rests against the eyecup wall, pull of the bridge member against the arm while the goggles are in use is imposed directly against that wall, whereby locking of great strength is afforded. Adjustment of the bridge member to the desired length once having been made, it will remain adjusted until readjustment is desired and effected.

The bridge adjusting means may be associated with both eyecups; or it may be associated with only one of them, in which case the flexible member 17-18 (or 19) is fixed to the other cup in any suitable manner, as shown, for example, on one of the cups in Fig. 1.

Goggles having this invention embodied therein may be placed on sale with the bridge lengthened to the maximum or nearly so. Then it is easy for a purchaser to shorten the bridge to bring the eyecups to the spaced relation required by him by simply pulling the flexible bridge member inwardly of one or both of the eyecups past the free end of the arm 23. During this movement, that end of the arm is flexed from the end of the hole 21 and away from the eyecup wall to the extent necessary for enlargements of the flexible bridge member to pass between the under side of the arm end and the reamed edge of the hole, the arm end returning to normal position after each release of an enlargement and finally locking the bridge member when adjustment is completed.

It is easy also to lengthen the bridge. This is accomplished by raising the locking end of the arm 23—as by prying with a knife blade or other suitable article—when the link member between enlargements may be pulled from between arm fingers, whereupon the flexible member may be pulled outwardly of the eyecup to the extent required, and then the arm returns to normal and locking position.

The movement of the spring arm 23 away from the eyecup wall to permit adjustment of the bridge member and its springing back after adjustment has been made is only in a plane substantially perpendicular to the axis of the eyecup. Movement in that plane is all that is required for release of the bridge member for adjustment and for snapping back after adjustment. It is not necessary to swing the arm laterally; in fact, that arm cannot be so swung because of the nature of its attachment to the eyecup wall.

The flexible bridge member may be associated initially with an eyecup by pushing the end ball 17 (or equivalent abutment) from the outside into the passage 21 and past the end of the arm 23, and then it may be grasped with the fingers and the member pulled in to the extent desired.

I claim:

1. An ophthalmic mounting comprising lens holders one of which has a wall perforated by a passage in its nasal side, a bridge member hav-

ing a series of abutments movable in said passage, and a spring arm fixed near one end to said wall and having on its other end portion a cup normally seated in an end of said passage to receive abutments of said member, there being a slot extending to said cup for reception of parts of said bridge member between its abutments, said cupped end portion being movable away from said wall to permit release of said bridge member from said cup and slot and its adjusting movement in said passage.

2. An ophthalmic mounting comprising lens holders one of which has a wall perforated by a passage in its nasal side, a bridge member having a series of abutments movable in said passage, and a spring arm fixed near one end to said wall and having on its other end portion a cup normally seated in an end of said passage to receive abutments of said bridge member and a flange outside of said cup contactable with said wall, there being a slot extending to said cup for reception of parts of said bridge member between its enlargements, said cupped end portion being movable away from said wall to permit release of said bridge member from said cup and slot and its adjusting movement in said passage.

3. An ophthalmic mounting comprising a pair of lens holders one of which has a wall perforated by a passage in its nasal side, a bridge member connected with the other of said lens holders and having a series of abutments movable in said passage, and a spring arm fixed near one end to said wall, having flexure only in a plane substantially perpendicular to the axis of the lens holder, and with its other end disposed over an end of said passage and normally between abutments of said bridge member, said latter end being movable by flexure of said arm away from said wall to permit adjusting movement of said bridge member in said passage.

4. An ophthalmic mounting comprising a pair of lens holders one of which has a wall perforated by a passage in its nasal side, a bridge member connected with the other of said lens holders and having a series of abutments in said passage, and a spring arm fixed near one end to said wall, having flexure only in a plane substantially perpendicular to the axis of the lens holder, and having a slot in its other end portion over an end of said passage in which said bridge member normally seats between abutments thereof, said slotted end portion being movable by flexure of said arm away from said wall to permit release of said bridge member from said slot and adjusting movement of said bridge member in said passage.

5. An ophthalmic mounting comprising lens holders one of which has a wall perforated by a passage in its nasal side, said passage at one end being enlarged at one side, a bridge member having a series of abutments movable in said passage, and a spring arm fixed at one end to said wall and at its free other end disposed over the enlarged end of said passage and normally positioned between abutments of said bridge member, said free end being movable by flexure of said arm away from said wall to permit traverse of bridge abutments under it in said end enlargement and adjusting movement of said bridge member.

6. An ophthalmic mounting comprising lens holders one of which has a wall perforated by a passage in its nasal side, said passage at one end being enlarged at one side, a bridge member having a series of abutments movable in said pas-

- sage, and a spring arm fixed at one end to said wall and at its free other end portion having a slot over the enlarged end of said passage in which said bridge member between abutments 5 thereof normally seats, said slotted end portion being movable by flexure of said arm away from said wall to permit release of said bridge member from said slot and traverse of bridge abutments under said end portion in said end enlargement 10 and adjusting movement of said bridge member.
7. An ophthalmic mounting comprising a pair of lens holders one of which has a wall perforated by a passage in its nasal side, a bridge member connected with the other of said lens 15 holders and having a series of abutments movable in said passage, and a spring arm fixed near one end to said wall, having flexure in a plane substantially perpendicular to the axis of the lens holder, and with its other end disposed over 20 an end of said passage and normally between abutments of said bridge member, said latter end being movable by flexure of said arm away from said wall to permit adjusting movement of said bridge member in said passage.
8. An ophthalmic mounting comprising a pair of lens holders one of which has a wall perforated by a passage in its nasal side, a bridge member connected with the other of said lens 5 holders and having a series of abutments in said passage, and a spring arm fixed near one end to said wall, having flexure in a plane substantially perpendicular to the axis of the lens holder, and having a slot in its other end portion over an end of said passage in which said bridge member normally seats between abutments thereof, said slotted end portion being movable by flexure of said arm away from said wall to permit release of said bridge member from said slot and adjusting movement of said bridge member in said passage.
